LUBRICATING HOLDER FOR KNIVES

Charles F. Eaton, Methuen, Mass., assignor of one-half to North American Holding Corporation, Syracuse, N. Y., a corporation of New York, and one-half to Parshad Holding Corporation, Syracuse, N. Y., a corporation of New York

Application March 8, 1938, Serial No. 194,611

4 Claims. (Cl. 91—38)

This invention relates to a lubricating holder for knives and the like applying tools, used, for example, in applying shoe filler material to the outsole cavities of shoes.

In accordance with conventional shoe making practices, a plastic filler is usually applied to the outsole cavity of a shoe, this operation being generally performed by means of a knife-like member, spatula, or similar tool. Due to the tacky character of both "hot" and "cold" fillers it is necessary to prevent the filler material from adhering to the blade of the applying tool, and to this end it is customary, when using a "hot" filler, to heat the blade periodically, and when using a "cold" filler, to provide the blade with a film of lubricant. Heretofore the latter procedure has been accomplished by dipping the blade into an open vessel containing kerosene or other suitable lubricant. Such a procedure is objectionable in that it not only involves the use of an open vessel, but also necessitates the removal of excess lubricant from the blade in order to prevent such lubricant from either staining the lasted shoe, or being mixed into the filler.

The principal objects of the present invention are to provide a lubricating holder for applying tools of the character described, which is not only capable of applying a film of lubricant to the blade, but effective to remove any excess lubricant, thereby avoiding the aforementioned objectionable features, and to provide a self-contained unit adapted to be secured either to the frame of a shoe filler press or to a bench or other support where it is readily accessible for use.

Further objects will be apparent from a consideration of the following description and accompanying drawings, wherein:

Fig. 1 is a front elevation of a self-contained unit constructed in accordance with the present invention and adapted to be fixed in position upon a bench or other suitable support;

Fig. 2 is a side elevation of the upper part of the holder unit shown in Fig. 1;

Fig. 3 is a section on the line 3—3 of Fig. 2;

Fig. 4 is a top plan view, partly broken away, of the unit shown in Figs. 1 and 2;

Fig. 5 is a bottom plan view of the cap member of the holder unit;

Fig. 6 is a top plan view of the base member of the holder unit;

Fig. 7 is a central longitudinal section of the drip cup associated with the holder unit;

Fig. 8 is a top plan view illustrating the manner in which a unit constructed in accordance

with the present invention, may be secured to the usual bracket arm of a shoe filler press;

Fig. 9 is a vertical section illustrating a modified embodiment of the invention;

Fig. 10 is a section on the line 10—10 of Fig. 9; and

Fig. 11 is a vertical section illustrating another embodiment of the invention.

The embodiment of the invention illustrated in Figs. 1 to 7 inclusive, comprises a standard or the like upright support 10, formed with a base adapted to be secured in fixed position upon a bench or the like. The standard 10 supports a knife-holding and lubricating device or unit which comprises a base member 11 and a cap member 12 seated thereon. The base member 11 is provided, adjacent to its opposite ends, with posts 13 which extend loosely through apertures 14 (Fig. 5) formed in corresponding parts of the cap member 12 so that the latter is free to move down and out from the base member. The upper ends of the posts 13 and threaded end are provided with thumb nuts 15 serving as abutments for spring 16, circumscribed about the posts and effective yieldingly to urge the cap member 12 downwardly across the base member 11.

The cap member 12 is formed on its under surface with a generally rectangular chamber or recess 17 (Fig. 5) across which extend a plurality of rails 18. A mass of suitable absorbent material such as felt pads 19 are disposed between the rails, as shown in Figs. 3, 5 and 6, and the bottom or lower surfaces of the felt pads are approximately flush with the bottom surfaces of the cap member 12 and rails 18. The base member 11 is likewise formed on its top side with a chamber or recess 20 (Fig. 6) across which extend a plurality of rails 21 and these rails also support a plurality of felt pads 22 whose top surfaces are approximately flush with the top surfaces of the member 11 and the rails 21. The chamber 20 of the base member 11 is formed with a lateral extension 23 (Figs. 3 and 6) which communicates with the lower end of a conduit 24 whose upper end supports a drip-cup mechanism 25 which may be of conventional construction.

The drip-cup 25 preferably comprises a transparent glass reservoir 26 adapted to hold a supply of suitable lubricant such as kerosene or the like 27 which may be replenished through a filler opening 28 (Fig. 7) at the upper end of the reservoir. A needle valve 29 (Fig. 7), forming part of the drip-cup mechanism, is constructed and arranged to be set in either its open or closed position by means of an operating handle 30.

When the handle 30 occupies the position shown in the dotted lines of Fig. 7, the valve 29 occupies its elevated or open position, and hence the lubricant is free to pass, by gravity, from the reservoir 26, drop by drop, into the upper end of the conduit 24, through which it passes downwardly into the chamber 20 of the base member 11. The felt pads 22 thus become saturated with the lubricant and by capillary action the upper parts 10 19 also become more or less saturated with the lubricant.

The construction and arrangement is such that an applying tool such as a knife K may be inserted with its blade occupying a position between the members 11 and 12 of the holding unit, as shown in Fig. 4, and when thus positioned the pads 19 and 22 apply a film of lubricant to the blade of the knife. As shown in Fig. 2, the base member 11 is preferably somewhat wider than the cap member 12 so that there is provided a guiding ledge or shelf 31 (Fig. 2) on which the free end of the knife blade may rest preparatory to insertion endwise into the holder, and the entrance of the knife blade into the holder may be facilitated by beveling the lower front edge of the cap member 12 as shown at 32. An important feature of the invention resides in the arrangement of the felt pads and rails, which is such that the latter not only provide retaining members anchoring the felt pads in position, but also serve as guides for the knife blade, which are effective to prevent the forward end of the blade from digging into and mutilating the felt pads. Accordingly, with this construction and arrangement the knife blade rides on the rails as it is inserted into and withdrawn from the holder and at the same time it contacts the adjacent surfaces of the felt pads and thus receives a lubricating film.

40 Referring to the construction illustrated in Fig. 8, it will be noted that the standard 10 shown in the previously described embodiment is dispensed with and the holder unit (members 11, 12 and associated parts) is connected directly with the bracket arm 33 which forms a part of a shoe press P, such as is shown in Patent No. 2,061,268 granted to me November 17, 1936. In order that the holder members 11 and 12 may be used either upon the standard 10 (Fig. 1) or upon the bracket 45 33 (Fig. 8), the base member 11 is formed with threaded apertures 34 (Fig. 3) in its rear edge, these apertures being spaced apart the same distance as the apertures 35 of the bracket 33 (Fig. 8) so as to accommodate screws or the like fastening elements 36 by means of which the holder unit is fastened to the bracket arm.

50 In the construction illustrated in Fig. 9, I have provided a barometric feed for the lubricant, which comprises a glass reservoir 26^a removably mounted within a cup or cap 37 formed integral with a conduit 38, the lower end of which is detachably mounted within an aperture formed in the base member 11^a of the holder unit, with its lower extremity being supported at a predetermined height above to the bottom surfaces of the felt pads 22. This construction and arrangement is such that when the level of the liquid within the base members falls below the lower end of the conduit 38, the lubricant will fall by 55 gravity downwardly into member 11^a until such flow is arrested by the closing of the lower end of the conduit due to the rise of the liquid within the member 11^a.

70 The outlet of the cap 37 is preferably formed with a conical valve seat 39 (Fig. 9) to receive

a conical-shaped valve member 40 having an elongate stem 41 which projects downwardly beyond the lower end of conduit 38 so that when the latter is inserted within the aperture 42 of the base member 11^a the engagement of the lower end of the stem with the base member opens the valve 40. When the conduit and reservoir are removed from the base member 11^a, the valve 40 closes and thus prevents lubricant from flowing into the base member. In this embodiment 75 the chamber 20^a of the base member is preferably formed along one side with a well or depression 43 and a groove or channel 44 extends from the well to beneath the felt pads 22 so as to conduct sufficient lubricant to each of the pads to insure the proper degree of saturation.

The embodiment shown in Fig. 11 comprises a base member 11^b which is formed at one side with a comparatively deep well 45 adapted to receive a supply of lubricant through a filler port 46 formed in the upper surface of the base member. The chamber 20^b is designed to receive one end of a wick 47 which extends upwardly and along the bottom wall of the member 11^b so as to contact each of the pads 22. With this construction 20 and arrangement the wick 47 feeds lubricant to the pads 22 which, in turn, feed lubricant to the upper pads 18, and in this manner the upper and lower pads are sufficiently saturated to insure proper lubrication to a knife blade inserted 30 therebetween.

In using a device constructed in accordance with the present invention, the absorbent material or felt pads deposit on the blade of the applying tool a thin continuous film of lubricant 35 which is sufficient to prevent adhesion of the plastic filler. With this construction and arrangement the saturation of the pads is such as to prevent excess lubricant from being deposited on the blade of the applying tool, regardless of 40 the time during which the blade is held between the felt pads, and upon withdrawal of the blade a uniform film of lubricant is insured. Moreover, since the supply reservoir and the applying surfaces of the felt pads are not exposed, there is 45 no danger of evaporation or accidental loss of lubricant.

50 While I have shown and described different desirable embodiments of the invention, it is to be understood that the disclosure is for the purpose of illustration only and that various changes in shape, proportion and arrangement of parts, as well as the substitution of equivalent elements for those herein shown and described may be made without departing from the spirit and scope 55 of the invention as set forth in the appended claims.

I claim:

1. A lubricating holder for knives and the like applying tools, comprising a base member having 60 a recessed area and a plurality of rails extending across and in spaced relation to the bottom of said recessed area, absorbent material interposed between said rails, means for supporting absorbent material in substantially contiguous relation to the absorbent material carried by said base member, a lubricant supply reservoir, and means for feeding lubricant from said reservoir to said recessed area.

2. A lubricating holder for knives and the like 70 applying tools, comprising a base member having a recessed area and a plurality of rails extending across and in spaced relation to the bottom of said recessed area, a cap member superposed on said base member, said cap member 75

having a recessed area on its under surface conforming substantially to that in said base member and a plurality of rails extending across its recessed area, absorbent material interposed between the rails in the base and cap members so that the under surface of the absorbent material carried by the cap member is substantially contiguous to the upper surface of the absorbent material carried by the base member, a lubricant reservoir, and means for conducting lubricant from said reservoir to the recessed area of one of said members.

3. A lubricant holder for knives and the like applying tools, comprising a base member having a recessed area, a layer of absorbent material disposed in said recessed area, means for supporting another layer of absorbent material in superposed relation to the first-mentioned layer, an enclosed lubricant supply reservoir disposed above said

base member, said reservoir having an outlet open in its lower end, and a supply line leading from said outlet opening to said recessed area, the lower end of said supply line being spaced from the bottom of said area so as to maintain a substantially constant level of lubricant therein.

4. A lubricant holder for knives and the like applying tools, comprising a base member shaped to define a substantially flat recessed area and a lubricant supply well communicating with said recessed area, absorbent material disposed in said recessed area, a wick extending from said well into said recessed area so as to contact the absorbent material therein, and a cap member superposed on said base member, said cap member carrying a mass of absorbent material conducting the absorbent material disposed in said recessed area.

CHARLES F. EATON.
